2,190,081

COUPLING

Edward M. Pfauser, Elm Grove, Wis., assignor to
 Blackhawk Mfg. Co., Milwaukee, Wis., a corporation of Wisconsin

Application January 22, 1938, Serial No. 186,288

2 Claims. (Cl. 287—119)

My present invention relates generally to improvements in coupling assemblages, and relates more specifically to improvements in the construction of detachable couplings especially adapted for attachment of a tool such as a wrench socket to a manipulating or driving member.

Generally defined, an object of this invention is to provide an improved coupling which is simple, compact and durable in construction, and which is also highly effective in use.

It has heretofore been proposed, as shown and described in my prior Patent No. 1,927,844, granted September 26, 1933, to provide a detachable coupling for socket wrenches or the like, comprising a spring pressed plunger slidably confined within a recess in the shank or driving member and cooperating with a transverse opening in the wrench socket or driven member. As shown and described in my prior reissue Patent No. Re. 19,287, granted August 2, 1934, it has also been proposed to provide a manually manipulable releasing button or plunger in the transverse opening of the wrench socket for effecting detachment of the coupling, and while both of these prior features have proven highly satisfactory and successful in actual commercial use, the assemblages have been rather difficult to manufacture and assemble, especially in the smaller sizes, primarily because of the method used to confine the locking and release elements in place. In these prior assemblages, it has been customary to retain the locking and release elements or plungers within their confining recesses or openings, by providing enlarged portions on the plungers and by peening the metal of the shank and socket over these enlarged plunger portions so as to provide plunger retaining abutments. If the plungers are assembled before heat treatment of the parts, the plunger actuating springs are detrimentally affected by the heat treatment, and scale will also form in the relatively inaccessible plunger confining pockets and will thus interfere with operation of the locking and release mechanism. If these plungers are assembled after the drive shank and wrench socket have been heat treated, it becomes difficult to peen the hardened metal without chipping or marring unless the heat treatment is undesirably restricted; but such application of the spring and plungers after heat treating, is most desirable because these parts are then unaffected by the heat treatment, sand blasting and plating, and the carrier members may be more readily cleaned and polished.

It is therefore a more specific object of my present invention to provide an improved coupling assemblage of the above described general type, wherein the spring and plungers may be most conveniently applied within their confining recesses, after heat treatment of the confining parts or members has been effected.

Another specific object of my invention is the provision of an improved detachable coupling assemblage which is applicable to driving and driven members of minimum diameter, and which may also be more conveniently applied to the carrying members, or removed therefrom if desired.

A further specific object of the invention is to provide a new and useful locking and release mechanism for couplings, which may be readily assembled or dismantled, and which is moreover highly effective in use.

Still another specific object of the invention is the provision of a compact and accurately formed coupling latch for socket wrenches which may be produced at moderate cost, and installed in socketed members having minimum external diameter, thus not only making it possible to use such tools in close quarters but also saving material in the manufacture of the sockets.

An additional specific object of my invention is to provide a spring pressed locking assemblage for couplings or the like, which can be conveniently assembled, or dismantled for replacement of the spring and plungers, and which may be applied after the carrier members have been completely finished.

These and other specific objects and advantages will be apparent from the following detailed description.

A clear conception of an embodiment of the invention, and of the mode of constructing and of utilizing couplings manufactured in accordance with the improvement, may be had by referring to the drawing accompanying and forming a part of this specification wherein like reference characters designate the same parts in the various views.

Fig. 1 is a central longitudinal section through a wrench socket and a fragment of a driving shank, showing these parts coupled and locked together with the aid of one of my improved coupling assemblages, and the section being a three-fold enlargement of the particular commercial device from which it was reproduced;

Fig. 2 is a similar section through the same assemblage, showing the release plunger de-

45

pressed preparatory to removal of the socket from the shank;

Fig. 3 is another similar section through the assemblage, showing the release plunger still depressed and the socket slipped partially off the shank;

Fig. 4 is still another similar section through the assemblage, showing the socket moved outwardly a distance sufficient to partially release the locking plunger;

Fig. 5 is an end view of the wrench socket alone, looking into the driving end thereof;

Fig. 6 is an opposite end view of the wrench socket;

Fig. 7 is a transverse section through the assemblage, taken along the line 7—7 of Fig. 3; and

Fig. 8 is a longitudinal section through a modified coupling assemblage.

While the invention has been shown herein as being applied to parts drawn to a relatively large scale in order to clearly illustrate the construction, it will be understood that in actual practice these parts may be either larger or much smaller in dimensions than shown, and has actually been embodied in very small and compact assemblages. Although I have shown the invention herein as being especially applicable to couplings for connecting a wrench socket to a driving shank of polygonal formation, it is not the intention to thereby unnecessarily restrict the scope.

Referring to Figs. 1 to 7 inclusive of the drawing, the improved coupling assemblage shown therein comprises in general, a shank member 9 having a square shank 10 at its extreme end and an abutment flange 11 at the inner end of the shank 10, the shank being provided between its ends with a recess 12 the central axis of which is disposed at an oblique angle relative to the longitudinal axis of the member 9; a socket member 13 having at one end a wrench socket 14 formed for coaction with polygonal or serrated nuts and bolt heads, and having its opposite end provided with a square socket 15 formed for free reception of the shank 10 and provided with a transverse bore or through opening 16 the central axis of which extends approximately perpendicular to the longitudinal axis of the member 13; a locking element or plunger 17 having an enlarged hollow inner portion 18 slideable within the recess 12, and a reduced solid outer portion movable outwardly beyond the bounding surface of the shank 10 and into the opening 16 by means of a helical compression spring 19 confined within the recess 12 and plunger portion 18; a release button or plunger 20 having inner and outer portions of substantially the same diameter separated by a flange 21, the inner portion 22 being slideable in the opening 16 toward and away from the solid outer portion of the locking plunger 17; and retaining bushings or collars 23, 24 for maintaining the plungers 17, 20 in their respective confining cavities.

While the shank 10 of the member 9 and the socket 15 of the member 13 are shown as being square in cross-section, these interfitting parts may obviously be of any other polygonal or interlocking formation, and are normally adapted to transmit motion from one member to the other. The end of the socket member adjoining the socket 15, may be provided with a chamfer 25 for depressing the locking plunger 17 as shown in Fig. 4 when the socket member 13 is being applied to the shank 10 of the member 9, but this chamfer is not essential and may be omitted.

When the members 9, 13 have been coupled to-

gether, the socket member 13 is movable to a slight extent along the shank 10 so as to insure a contact between the chamfered end of the member 13 and the flange 11 as illustrated in Fig. 1. The bushings or collars 23, 24 may be of like construction and formed of sheet metal, and each of these collars has an annular inwardly projecting integral flange 26. The interior of the collar 23 may have the same diameter as the recess 12 and the flange 26 of this collar 23 is 10 cooperable with the abutment formed by the enlarged plunger portion 18 of the locking plunger 17 to limit the outward motion of this plunger. The interior of the collar 24 is of slightly larger diameter than the flange 21 of the releasing plunger 20; and the flange 26 of this collar 24 is cooperable with the flange 21 so as to limit the outward movement of the plunger 20, while the abutment formed by the reduced bore 16 limits the inward motion of this plunger. The sleeve collars 23, 24 are press fitted within their receiving bores in the members 9, 13, respectively, and thus enable application of the spring 19 and plungers 17, 20 after the members 9, 13 have been finally heat treated and finished.

Referring to the modified coupling assemblage shown in Fig. 8, this assemblage again comprises in general a shank member 9 having a square shank 10 and a flange 11 adjoining the shank 10, this shank having an inclined recess 12 of uniform diameter throughout its depth; a socket member 13 provided with a square socket 15 formed for free reception of the shank 10 and being provided with a transverse bore 16 of uniform diameter extending substantially perpendicular to the axis of the member 13; a hollow locking element or plunger 17 having an enlarged external flange 18' and being movable outwardly by means of a compression spring 19; a release element or plunger 20 having an enlarged external flange 21; and retaining bushings or collars 23, 24 within which the flanges 18', 21 are slideable. In this modified assemblage, the chamfer 25 has been omitted, and the plunger retaining collars 23, 24 are provided with inwardly projecting flanges 26 at both ends thereof as by spinning or otherwise distorting these ends. The plungers 17, 20 of the modified form are axially slideable directly within their confining collars 23, 24 and the flanges 18', 21 are cooperable with 50 the opposite end flanges 26 of these collars, respectively, to limit the travel or movement of the plungers. In this modified construction, the recess 12 and opening or bore 16 may be formed by a simple drilling operation and may be more 55 readily cleaned after the heat treatment has been effected. The collars 23, 24 may be pressed into the recess 12 and bore 16, and the modified structure may be assembled or dismantled, and functions precisely the same as the embodiment 60 shown in Figs. 1 to 7 inclusive.

When manufacturing the improved couplings of both embodiments, the members 9, 13 are first machined, heat treated, sand blasted and plated or polished, before the plungers 17, 20 are applied thereto. By thus finishing these members before application of the plungers they may be properly heat treated and the recess 12 and opening 16 may be thoroughly cleaned preparatory to application of the plungers. The spring 19, locking plunger 17, and collar 23 may then be inserted within the recess 12, the retaining collar 23 being pressed within its receiving bore so as to maintain the locking plunger assemblage in place. The spring 19 will then tend to force the 75

locking plunger 17 outwardly to the position shown in Fig. 1, at all times. The releasing plunger 20 may be applied to the socket member 13 by pressing the collar 24 into its receiving bore, whereupon the plunger 20 will be freely slideable within the opening 16 and within the limits of travel of the flange 21. The flange 21 of the releasing plunger 20 should preferably be engageable with its motion limiting abutments 10 so as to prevent the inner end of the plunger 20 from projecting inwardly into the socket 15.

With the structure thus assembled, the socket 15 may be applied to the shank 10 and the member 13 may be slipped rearwardly toward the flange 11 on the member 10. As the chamfer 25 engages the projecting plunger 17 and the rearward movement of the socket member 13 is continued, the plunger 17 will be forced inwardly as indicated in Fig. 4. Continued inward movement 20 of the member 13 will cause the plunger 17 to remain in the position shown in Fig. 3 until the plunger 17 reaches the opening 16, whereupon the spring 12 will become effective to move the plunger 17 and the plunger 20 outwardly into the position shown in Fig. 1. The members 9, 13 will then be locked together and rotary motion 25 may be imparted from the driving member 9 to the socket member 13 in any suitable manner.

In order to release the lock, it is only necessary 30 to manually press the plunger 20 inwardly to the position shown in Fig. 2 so as to push the locking plunger 17 out of the opening 16. The sleeve 13 may then be pulled outwardly as shown in Fig. 3 and may be subsequently pulled outwardly to a greater extent so as to gradually release 35 the locking plunger 17 as indicated in Fig. 4. It will thus be noted that the improved locking mechanism may be utilized to automatically lock the members 9, 13 together, and may be quickly released to unlock these members by merely pressing the release plunger 20.

From the foregoing description it will be apparent that the provision of locking and release 40 plungers which may be applied to the coupling members after heat treatment and final finishing thereof, facilitates manufacture of the assemblage and enables more perfect heat treatment of the driving and driven members. This application of the plungers after heat treatment of the 45 coupling members also permits more effective finishing of the members by sand blasting, buffing or plating, without interference by the locking and release plungers. The use of the retaining collars 23, 24 also insures production of a neater final assemblage and permits application 50 of these locking and release plungers to small shank and socket members than was heretofore possible. The collars 23, 24 while being driven into their retaining bores, may if necessary be removed to permit replacement of the plungers 17, 20 and of the spring 19. The collars 23, 24 may obviously be formed either as shown in Figs. 1 to 7 inclusive, or as shown in Fig. 8, or in any other manner which will accomplish the same 55 results; and the improvement will obviously permit reduction of the diameter of the rear portion of the socket member 13 to a minimum by virtue of the fact that obviation of the prior peening

operation enables reduction of the shank 10 to minimum cross-section. As previously indicated, the chamfer 25 is not essential, and the locking plunger 17 may obviously be modified in shape and may even be replaced by a ball lock. The 5 assemblage has proven highly practical and successful in actual commercial use, and the locking elements may be applied at moderate cost.

It should be understood that it is not desired to limit this invention to the exact details of construction or to the precise mode of operation herein shown and described, for various modifications within the scope of the claims may occur to persons skilled in the art.

I claim:

1. In a device comprising an outer member having an opening, an inner member movable longitudinally within said opening, one of said members having a transverse bore and the other having a recess alineable with the open end of said bore, and a detent plunger slideable in said bore and being engageable with said recess to hold said members assembled; the improvement comprising the formation of said bore with enlarged diameter at its end adjacent said recess, the formation of said detent plunger with large and small diameters separated by an abutment and with the portion of larger diameter slidably coacting with said bore portion of smallest diameter while the portion of smallest diameter is cooperable with said recess to latch the members together, and a guiding and retaining collar for the plunger snugly fitted within said bore portion of larger diameter and having an inner diameter approximately equal to and alineable with the bore portion of smallest diameter so as to also slidably coat with said plunger portion of largest diameter, said collar having an inwardly projecting integral flange at its outer end with which said plunger portion of smallest diameter is constantly slidably cooperable and which flange is engageable with said abutment to limit the outward movement of the plunger.

2. In a device comprising an outer member having an opening, an inner member movable longitudinally within said opening, said members having alineable transverse recesses, a detent element slideable in one of said recesses and being cooperable with the other to latch said members assembled, and a release button element 40 slideable in the other of said recesses and being cooperable with said detent element to release the latch; the improvement comprising the formation of one of said recesses with a portion of enlarged diameter, the formation of the slideable element therein with large and small diameters separated by an abutment, and a guiding and retaining collar for said element snugly fitted within said recess portion of larger diameter and slidably embracing said element portion of largest diameter, said collar having an inwardly projecting integral end flange with which said element portion of smallest diameter is constantly slidably cooperable and which flange is engageable with said abutment to limit the movement of said element.

EDWARD M. PFAUSER.
